United States Patent Office

Des. 232,203

Patented July 30, 1974

232,203

SERVING DISH

Margaret W. Montgomery, 11046 Harney St.,
Omaha, Nebr. 68154

Filed Dec. 20, 1972, Ser. No. 317,084

Term of patent 14 years

Int. Cl. D7—01

U.S. Cl. D7—1

FIG. 1

FIG. 3

FIG. 5

FIG. 7

FIG. 2

FIG. 4

FIG. 6FIG. 8FIG. 9FIG. 1 is a bottom perspective view of a serving dish showing my new design;

FIG. 2 is a top plan view thereof on an enlarged scale;

FIG. 3 is a front elevational view thereof;

FIG. 4 is a bottom plan view thereof;

FIG. 5 is a cross-sectional elevational view taken along lines 5—5 of FIG. 2 and FIG. 4;

FIG. 6 is a cross-sectional elevational view taken along lines 6—6 of FIG. 2 and FIG. 4;

FIG. 7 is a rear elevational view thereof;

FIG. 8 is a right side elevational view of FIG. 2; and

FIG. 9 is a left side elevational view of FIG. 2.

I claim:

The ornamental design for a serving dish, as shown.
